UNITED STATES PATENT OFFICE.

MARIUS GREENSPAN, OF CHICAGO, ILLINOIS.

DESIGN FOR AN AUTOMOBILE-TIRE.

57,431.

Specification for Design.

Patented Mar. 29, 1921.

Application filed May 23, 1919. Serial No. 299,356. Term of patent 14 years.

To all whom it may concern:

Be it known that I, MARIUS GREENSPAN, a citizen of the United States, residing at Chicago, in the county of Cook and State of Illinois, have invented a new, original, and ornamental Design for an Automobile-Tire, of which the following is a specification, reference being had to the accompanying drawing, in which—

Figure 1 is a plan view of the design, and

Fig. 2 is a cross section thereof.

I claim:—

The ornamental design for an automobile tire, as shown.

In testimony whereof I affix my signature.

MARIUS GREENSPAN.
